(57) **CLAIM**

The ornamental design for a loop lock collar for a dispensing container, as shown and described.

DESCRIPTION

FIG. 1 is a front perspective view of a loop lock collar for a dispensing container in accordance with the present design with the loop lock shown in a stored position.

FIG. 2 is a front elevational view of thereof.

FIG. 3 is a back elevational view thereof.

FIG. 4 is a left side elevational view thereof.

FIG. 5 is a right side elevational view thereof.

FIG. 6 is a top view thereof.

FIG. 7 is a bottom view thereof.

FIG. 8 is a perspective view of the loop lock collar for a dispensing container shown in a position of use installed on an unclaimed dispensing container drawn in broken lines with the loop lock shown in the stored position.

FIG. 9 is a perspective view of the loop lock collar for a dispensing container shown in a position of use installed on the unclaimed dispensing container drawn in broken lines with the loop lock deployed in an open position.

FIG. 10 is a perspective view of the loop lock collar for a dispensing container shown in a position of use installed on the unclaimed dispensing container drawn in broken lines with the loop lock deployed in a cap locking position; and, FIG. 11 is a front elevational view of the loop lock collar for a dispensing container shown in a position of use installed on the unclaimed dispensing container drawn in broken lines with the loop lock deployed in the cap locking position.

The dot-dash-dot broken lines depict the boundaries of the claim and form no part thereof. The dash-dash broken lines showing a dispensing container illustrate environment and form no part of the claimed design. All other broken lines depict portions of the loop lock collar for a dispensing container that form no part of the claimed design.

1 Claim, 11 Drawing Sheets
